United States Patent Office.

LEANDER POLLOCK, OF MATTEAWAN, NEW YORK, ASSIGNOR TO HIMSELF
AND JOHN P. SCHENCK, JR., OF SAME PLACE.

Letters Patent No. 72,080, dated December 10, 1867.

IMPROVED RAILWAY-CHAIR.

The Schedule referred to in these Letters Patent and making part of the same.

TO ALL WHOM IT MAY CONCERN:

Be it known that I, LEANDER POLLOCK, of Matteawan, in the county of Dutchess, and State of New York, have invented a new and improved Railroad-Chair; and I do hereby declare that the following is a full, clear, and exact description thereof, which will enable others skilled in the art to make and use the same, reference being had to the accompanying drawings, forming part of this specification, in which—

Figures 1 and 2 represent transverse sectional views of my invention.

Figure 3 is a plan or top view of the same.

Similar letters of reference indicate corresponding parts.

This invention relates to a new railroad-chair, which is so arranged that the heavier the rail is loaded, the tighter will it be held between the cheeks of the chair.

The invention consists in making the chair of two pieces, each piece consisting of one cheek and of a portion of the base. When the two pieces are connected, the base of one rests upon the base of the other, the line of division between the two bases being inclined, so that as the rail presses upon the upper base it will tend to force the same downward on the incline, whereby the two cheeks would be brought towards each other.

A represents one portion, and B the other portion forming my improved railroad-chair. The portion A consists of one cheek, *a*, and of the lower part, *b*, of the base of the chair. The surface of the base *b* is inclined towards the cheek *a*, so that the base *b* is thicker the further it is from the cheek *a*. The portion B of the chair consists of the opposite cheek *c*, and of the upper portion *d* of the base of the chair. The under side of the base *d* is inclined, so as to make the base *d* the thicker the further it is from the cheek *c*. When the two portions are placed together, the base *d* covers the base *b*, and the edge of the base *d* rests against the cheek *a*, as shown. The tendency of the portion B of the chair would be, especially if it is weighted, to slide upon the inclined surface of the base *b* towards the cheek *a*, and, consequently, the two cheeks *a* and *c* constantly clamp the rail between them. The portion A of the chair is fastened to the sleeper by means of spikes *e*, inserted through an outer portion of the cheek, or otherwise; and the portion B is fastened by means of spikes *ff*, fitted through slots in the outer part of its cheek, and through the base *b* of the portion A into the sleeper. By means of these slots, the motion of the cheek *c* toward *a* is not prevented, while the outward or sideway motion of the portion B is hindered. Between the edge of the base *d* and the cheek *a* may be interposed a layer, *g*, of rubber, leather, wood, or other elastic material, as indicated in fig. 2. Sand would thereby be prevented from filling the space, and from injuring the operation of the device.

Having thus described my invention, what I claim as new, and desire to secure by Letters Patent, is—

1. A railroad-chair, which is divided, by an inclined line drawn through the base, into two parts, A and B, each part carrying one of the cheeks, and all made and operating substantially as herein shown and described.
2. Interposing an elastic plate, *g*, between the edge of the upper base *d* and the stationary cheek *a*, substantially as and for the purpose herein shown and described.

LEANDER POLLOCK.
